BURGLAR ALARM

Floyd M. Edwards, 2209 Otis Drive,
Alameda, Calif. 94501

Filed Mar. 10, 1967, Ser. No. 6,172

Term of patent 3½ years

(Cl. D72—1)

FIG. 1 is a perspective view of the front, left end, and bottom of the alarm of my design;

FIG. 2 is a front view of the alarm shown in FIG. 1;

FIG. 3 is a top view of the alarm shown in FIG. 1;

FIG. 4 is a rear view of the alarm shown in FIG. 1; and

FIG. 5 is a right end view of the alarm shown in FIG. 1.

The dominant features of my design reside in the portion shown in full lines.

I claim:

The ornamental design for a burglar alarm, as shown and described.
